UNITED STATES PATENT OFFICE.

ROBERT GEISLER, OF LEIPSIC, GERMANY, ASSIGNOR TO KNAUTH & CO., OF SAME PLACE.

UMBRELLA AND PARASOL.

SPECIFICATION forming part of Letters Patent No. 269,846, dated January 2, 1883.

Application filed May 1, 1882. (No model.) Patented in Germany August 12, 1880, No. 12,839; in England January 19, 1882, No. 273; in Austria-Hungary March 4, 1882, No. 2,953 and No. 8,319, and in France April 29, 1882, No. 147,432.

To all whom it may concern:

Be it known that I, ROBERT GEISLER, of Leipsic, in the Empire of Germany, have invented a new and useful Improvement in Umbrellas and Parasols, of which the following is a specification.

Figure 1 is a side view of my improved umbrella, showing it contracted; Fig. 2, a similar view of the same, showing it expanded. Figs. 3, 4, 5, 6, 7, 8, and 9 are detail views, herein after more fully referred to.

The object of this invention is to produce a parasol or umbrella which when folded together will contract a spring for throwing it open the moment a catch at the handle is released.

The invention consists in the new combination of parts hereinafter more fully described.

In the drawings, the letter A represents the stick of the umbrella, having a handle, B, and in this handle a spring-catch or holding-pin, a, is secured, such as that shown in Fig. 9, or an L-shaped slot or equivalent means of fastening the lower runner, D. The runner D has a horizontal slot, b, for the catch a to engage in, as shown in Fig. 9, and may, if desired, be swiveled and provided with an L-shaped slot, so that it can be turned to engage with a rigid catch-pin, a. The runner D carries the inner ends of the braces E, which braces are pivoted to the umbrella-ribs F at or near their middle—that is to say, at or near the middle of the ribs F. The upper and inner ends of the ribs F are secured in a crown-ring, G, that is rigidly secured in the upper portion of the stem A. With the ribs F, at or about the points where the braces E join them, are also flexibly united other braces, J, whose inner ends are fastened to a supplemental runner, H, that rests when the parasol or umbrella is expanded on a cushion, d, which surrounds the stem A and bears on a shoulder, e, of the said stem, as shown in Figs. 2 and 5. On the bottom of the runner H rests the lower end of a coiled spring, I, which surrounds the stem A and extends from the bottom of the runner H as far up as the crown-ring G. Now, whenever the umbrella is to be

folded together, as in Fig. 1, the runner D is pulled down and pulls the braces E down with it, thereby also carrying the ribs F into position 50 practically parallel to the stem, and likewise the braces J; but these latter braces, in order to attain this position, lift their runner H, as shown in Fig. 1, and thereby contract the spring I. In this position the umbrella is locked by the catch 55 a. Whenever this catch is touched, or the runner D turned aside to open the umbrella the spring I will immediately expand, lower the runner H against the cushion d, thereby throwing the ribs and braces into the partially horizontal position which is shown in Fig. 2, and opening the parasol or umbrella. Thus, by means of this invention, the labor of opening an umbrella or parasol is avoided, and in case of storm, or where a person has only one hand 60 to use, he can still open the umbrella or parasol by merely touching the catch a or turning the runner D.

In order to facilitate the folding together of the braces and ribs E, J, and F, they are made 70 U-shaped in cross-section, as shown in Fig. 3, and adapted to fold the ribs F into the braces J, as clearly shown in Fig. 4. The spring I surrounds the upper part of the stem A, and is exposed to view, so that it can be reached 75 for repair if out of order. This also enables the stem to remain continuous from one end of the parasol to the other.

I claim—

1. In an umbrella or parasol, the combination of the ribs F and braces E, ordinary runner D, and catch a, with the additional braces J, runner H, and with the spring I, which surrounds the stem A, all arranged for operation substantially as described. 80
2. The cushion d, combined with the shoulered stem A, runner H, extra braces J, spring I, ribs F, braces E, and runner D, for operation on an umbrella or parasol, substantially as specified. 85

ROBERT GEISLER.
